UNITED STATES PATENT OFFICE

PAUL F. YUNGLING, OF LOS ANGELES, CALIFORNIA, ASSIGNOR TO SCOTT-ROSS AND COMPANY, OF LOS ANGELES, CALIFORNIA, A CORPORATION OF DELAWARE

FLUID-OPERATED PUMP

Application filed June 27, 1928. Serial No. 288,691.

This invention relates to fluid-operated pumps of the type employed, for example, in oil wells, and an important object is to improve the operation of this type of pump.

This invention is an improvement over the fluid-operated pump disclosed in my Patent No. 1,764,482, granted June 17, 1930, and an important object of the present invention is to materially reduce the friction 10 on the power fluid. In the above mentioned prior application, the pump employs two lines of pipe inside of the well casing, an outer pipe or tubing for the oil that is being raised from the well and an inner pipe or 15 macaroni, as it is generally termed, for induction of the power fluid from the surface pump to the cylinder of the pump in the well. In the present construction, I eliminate the macaroni, of comparatively small 20 diameter, and, instead, elevate the oil through the annular space that lies between the well casing and a tubing through which the power fluid is inducted. By this construction, as is readily understood, I employ 25 but two lines of pipe, the same as is employed in wells that are pumped with a pump that is operated by sucker rods. Since I pump the oil through the casing, I reduce the fluid friction between said oil and casing 30 by a considerable amount and, furthermore, since only one string of tubing is required inside of the casing, the said string may be made of considerably larger diameter than the macaroni tubing formerly employed, thus materially reducing the fluid 35 friction of the power fluid on the inner tubing.

Another object is ease of installing of the pump in the well and removal of the pump 40 from said well.

Other important objects and advantages will appear in the subjoined detailed description.

The accompanying drawings illustrate 45 the invention.

Figures 1 to 4 inclusive are vertical sections of a construction embodying my new fluid-operated pump, portions being broken away to contract some of the views. The 50 views taken in numerical order represent successive portions of the pump beginning at the upper end thereof.

Figure 5 is a horizontal section on the line indicated by 5—5 of Figure 4.

Figure 6 is a fragmental vertical section 55 showing the packer elements in the positions they occupy prior to seating of the packer.

Figure 7 is a diagrammatic sectional view showing the valves, the ports controlled by said valves and the ducts or passages in the 60 valve body.

Figures 8, 9 and 10 are enlarged horizontal sections on the lines indicated by 8—8, 9—9, 10—10, respectively, in Figures 1, 2 and 3, respectively.

Figure 11 is a broken vertical midsection 65 combining Figures 1 to 4, inclusive, the diameters of some of the parts relative to their lengths being exaggerated.

Figure 12 is a longitudinal mid-section of 70 the valve mechanism, fragments of tubing being indicated in broken lines and connected with said mechanism.

Figure 13 is a longitudinal section taken on a plane at substantially ninety degrees 75 from the plane of section of Figure 12.

Figure 14 is a horizontal section on the line indicated by 14—14, Figure 12.

Figures 15 and 16 are horizontal sections 80 on the lines indicated by 15—15, 16—16, respectively, Figure 13.

Figure 17 is a fragmental sectional detail 85 of the connection between one of the heads and one of the tubular sections of the valve mechanism.

Figure 18 is a fragmental sectional detail on the line indicated by 18—18, Figure 12.

There are provided an inner and an outer 90 string of pipe or tubing, the inner string 15 being that through which the power fluid is inducted and the outer string 16 being that through which the oil or other fluid, produced by the well, is pumped. The tubing 16 is generally termed a well casing and, where it passes through the producing strata, 95 is provided with perforations 17 to admit the well fluid into the interior of the casing. As is general, there is provided an unperforated portion 18 of the casing below the perforations so as to insure, as far as pos- 100

sible, against the entrance of gas, sand and the like into the casing.

Above the perforations 17 I provide a packer, indicated in general at 19, to separate the well fluid induction space 20 below the packer from the well fluid eduction or pumping space 21 above the packer. The packer 19, though it may be of any suitable construction, will be described more in detail hereinafter in order to make clear how the packer is set and loosened.

The pump tubing 15, which constitutes the conduit for the power fluid, extends through the packer 19 and has its lower end forming a sleeve 22 that closely fits and is telescoped over a tubing section 23 which, preferably, is provided with a perforated portion 24, that has an outside diameter that is less than the inside diameter of that portion of the tubing 15 that is positioned adjacent to the perforated portion 24 so that power fluid can freely pass downwardly around the perforated portion and through the perforations to the interior of the tubing section 23. The power fluid, owing to the relatively tight fit between the sleeve 22 and tubing section 23, is prevented from going further down the well.

The lower end of the tubing section 23 is connected, to a casing or housing 25 of a suitable valve mechanism which is indicated in general by character 26. The details of construction of the valve mechanism 26 will be described hereinafter. This valve mechanism is the subject of my copending application filed June 13, 1928, Serial Number 285,025.

The lower end of the casing 25 is connected to a tube 27 that forms a conduit for the passage of power fluid between the valve mechanism and the lower end of a motor cylinder 28 that is positioned inside of and, preferably, concentric of the tube 27. The cylinder 28 is provided near its lower end with ports 29 communicating the interior of the cylinder with the annular space 30 that lies between the cylinder and the tube 27. The lower end of the cylinder 28 is closed by a plug 31.

Below the tube 27, and also below the cylinder 28 and connected thereto, is a pump working barrel 32 and at the lower end of the working barrel is a standing valve 33 of any suitable or well known construction. In this instance, connected with the standing valve 33, and projecting downwardly therefrom, is a gas anchor 34 which may be omitted, in case its use is not required. The gas anchor 34 is customarily provided with perforations 35 through which the well fluid passes from the interior of the casing to the interior of the gas anchor.

Working in the working barrel 32, is a pump plunger 36 provided, in this instance, at its lower end with a valve 37 and at its

upper end with a valve 38. The valves 37, 38 may be of any well known type of plunger valves and, in fact, the working barrel and plunger may be of any suitable well known type.

Working within the cylinder 28 is a piston 39 which is positively connected with the pump plunger, in this instance, by a connecting rod comprising upper and lower sections 40, 41 of different diameters, the upper section having the smaller diameter and the lower section having the larger diameter. The lower section 41 has a sliding fit in an upward extension 42 of the working barrel and, in fact, the rod section 41 constitutes an upward extension of the pump plunger as it, also, functions as a plunger, since it pumps the well fluid on its down-stroke. The rod sections 40, 41 constitute a stepped connecting rod, the advantage thereof being that it thereby cuts down the volume of liquid that is pumped on the up-stroke of the plunger while, at the same time, providing for a relatively great cross sectional area of the bore of the cylinder so that the power fluid will be more effective in raising the piston. It will be noted that the cross sectional area of the connecting rod section 41 that enters the working barrel is, preferably, about one half of that of the plunger so that the volumes of liquid discharged on the up and down strokes of the plunger will be approximately equal, thus to keep the fluid column moving constantly and avoiding settling of sand and other foreign, solid particles that may be in the fluid column. This prevents sanding up of the pump. By keeping the fluid column moving constantly, economy in the use of power results since it is not necessary to overcome the inertia of a stationary column of liquid, as would be the case if the fluid column were raised on only the up stroke of the plunger. The connecting rod section 40 has a close sliding fit in a sleeve 43 that is positioned in the upper end of the extension 42.

A suitable means is provided for connecting the piston with the valve mechanism 26 so as to effect operation of said valve mechanism upon the up and down motion of the piston. These means, in this instance, include a lost motion device comprising a rod 44 projecting through the upper head 45 of the cylinder, the upper end of said rod connecting with the moving parts of the valve mechanism. The rod 44 is provided with a lower shoulder 46 and an upper shoulder 47, said shoulders, in this instance, being in the form of coil springs surrounding and connected with the rod 44. The shoulder 47 engages the outer end of the head 45 on the upstroke of the piston and the shoulder 46 engages the inner end of the head 45, on the downstroke of the pis-

ton. The lost motion connection is provided, in this instance, because of the particular construction of the valve mechanism and is only sufficiently described so that the operative connection between the piston and valve mechanism will be understood.

Referring more particularly to Figure 7, which is merely a diagrammatic view, the valves of the valve mechanism are indicated 10 at 48, 49, 50 and 51. The valves 48, 49 control ports 52, 53, respectively, that open downwardly from the interior of the tubing section 23. The valve 50 controls a port 54 that communicates at its lower end with 15 the annular passage 30 and that communicates at its upper end with an annular passage 55 that is formed between the valve mechanism casing 25 and a tube 56 that is positioned inside of and 20 spaced from the casing 16. The tubing 56 has a leak-proof connection at its upper end with the packer 19 and at its lower end with a seat member 57. The tubing 56 separates 25 the annular passage 55 from the well fluid induction space 20.

The valve 51 controls a port 58 that communicates at its lower end with the interior 30 of a tube 59 that has a liquid-tight connection at its upper end with the valve mechanism and at its lower end with the upper end of the cylinder. The upper end of the port 58 communicates with the annular passage 55. The bore of the tubing 59 thus forms a conduit for inducting the power 35 fluid between the valve mechanism and the upper end of the cylinder.

Since the bore of the working barrel extension 42 is of considerably larger diameter than the bore of the sleeve 43, there is 40 formed a space 60 inside of the extension 42, between the lower end of the sleeve 43 and the upper end of the connecting rod section 41 and, accordingly, it is advisable to provide a breather for said space. Such 45 breather, in this instance, is formed of one or more laterally extending tubes 61 that communicate at their inner ends with the space 60 and that pass through the tube 56 and communicate at their outer ends with 50 the annular passage 55. Thus, the rod section 41 on its upstroke works against a fluid pressure that is only that of the well.

The packer 19, in this instance, is constructed as follows:

55 There is an inner packer member 62 forming an outwardly projecting annular shoulder 63, and there is an outer packer element 64. The upper end of the element 64 forms a shoulder 65. Between the shoulders 63 and 65 is the packing 66, preferably of readily disintegratable material such, for example, as metallic packing. The lower portion of the packer element 62 is provided with external screw threads 67 adapted, 60 when the elements 62, 64 are relatively posi- tioned as in Figure 6, to engage the internal screw threads 68 in the upper end of the section 64. The element 62 has an unthreaded portion 69 extending from the threads 67 to the shoulder 63, so that when the element 62 is turned in a direction to screw it downwardly on the section 64, the screw threads 67 will disengage the screw threads 68 and permit the element 62 to be forced downwardly so as to compress the packing against 70 the outer face of the element 62 and inner face of the casing 16. Forcing of the element 62 downwardly is effected by engagement therewith of an external shoulder 70 on the tubing 15. Thus, the packer can be set by permitting the entire weight of the tubing 15 to be imposed upon the element 75 62. There is a spline connection between the tubing 15 and the packer element 62 so as to permit of longitudinal movement of the tubing 15 within the element 62 and so that rotation of the element 62 can be effected, when desired, by turning the tubing 15. The spline connection, in this instance, comprises splines 71 mounted longitudinally on 80 the tubing and grooves 72 in the element 62 to receive the splines 71.

In order to loosen the packer 19, when it is desired to pull the pump, the lower end of the tubing portion 73 that slides over the section 23 is provided with an external shoulder 74 adapted, when the tubing section 73 is raised to the position shown in Figure 6, to engage the lower end of the packer element 62 so as to raise said packer section, 90 the weight imposed on the section 62 having been removed when the tubing section 73 is raised, because of the shoulder 70 being lifted off the section 62. It will be readily seen that after the packer has been thus loosened, 95 the entire pump can be pulled from the well by pulling up on the tubing 15, since the weight of all of the pump parts below the shoulder 74 is imposed on said shoulder. In 100 this particular instance, the shoulder 74 is formed by the upper end of a collar 75, that is screw threaded onto the lower end of the tubing section 73. When the tubing 15 is thus raised to withdraw the pump, the packing 66 is disintegrated by friction thereof 105 against the inner face of the casing 16, thus freeing the packer so that there is no difficulty in pulling the same out with the pump. There is a slight clearance 76 between the packer section 64 and the inner 110 face of the casing 16, so that some of the disintegrated packing can readily pass through said clearance, when the packer is pulled upwardly. The lower end of the tube 27 is sealed by a nut 761 which is screwed onto the lower end of the plug 31. The fluid being pumped can pass upwardly through the packer from the bore of the tube 56, by reason of the provision of vertical ducts 82 115 120 125 130

formed in the packer element 62. Thus said fluid can pass into the casing.

On the seat member 57 is adapted to removably seat a reducing coupling 77 which is screw threaded onto the lower end of a nipple 78 that is screw threaded into the lower end of the working barrel extension 42. Within the coupling 77 is a chamber 79 and the connecting rod section 41 passes through an enlarged bore portion 80 in the coupling, said bore portion extending downwardly from the chamber 79 to the lower end of the coupling. The bore portion 80 is of somewhat larger diameter than the rod section 41, thus affording passage for the fluid being pumped. Opening upwardly from the chamber 79 and communicating with the bore of the tube 56 are ports 81. The lower end of the bore 80 communicates with the upper end of the working barrel.

The upper end of the casing is closed by a head 83, the interior of which communicates with a pipe line 84 by which the pumped fluid may be conducted to any desired place. The head 83 is provided with a stuffing box 85 which surrounds the tubing 15 that projects upwardly through said stuffing box. The upper end of the tubing 15 is adapted to be connected to a suitable pump, the source of the power fluid that is under pressure for operating the pump.

The body of the valve mechanism 26 comprises a number of sections, an upper section or head 109, a lower section or head 110, and tubular intermediate sections 111, 112, which connect passages 113, 114 in the head 109 with passages 115, 116, respectively, in the head 110. To secure the members 111, 112 to the heads, the ends of the sections 111, 112 are provided with ends 117 that telescope into recesses 118 formed in the heads 109, 110, there being shoulders 119 on the sections 111, 112 outside of the ends 117 for the heads 109, 110 to seat against. Copper gaskets 20 are placed in the recesses 118 between the ends 117 and the heads. Near their ends, the sections 111, 112 are provided with flanges 121 in which are holes 122 to receive studs 123 that project from the heads, nuts 124 on said studs seating against the flanges 121 to hold said flanges securely to the heads.

The port 58 communicates with the passage 113 and the port 52 opens to the upper end of the head 9 and communicates with the passage 14. The port 58 opens to the lower end of the head 110 and also to the periphery of said head. The port 54 opens to the periphery of the head 110 and communicates with the chamber 33 in which the head of the valve 50 is positioned. Connected with the head 110 is a tubular member 27, which affords an annular passage 135 communicating with the chamber 133. This passage 135 is intended to connect with

one end of the cylinder of the pump as will appear hereinafter.

The sections 111, 112 are spaced, and in the space thus formed is mounted the mechanism that operates the stems of the valves. The stems 136, 137 of the valves 49, 48 project downwardly through the head 109 into a chamber 138 which is formed between the heads 109, 110 and cover plates 139 secured by screws 140 to the heads 109, 110. The stems 141, 142 of the valves 51, 50 project upwardly through the head 110 and into the chamber 138. The tubular sections 111, 112 are also positioned in the chamber 138.

In the space between the sections 111, 112 are mounted cams 143, 144 which are caused to rock by a pin 145 that projects through cam slots 146, 147 in the cams 143, 144, respectively. The pin 145, in this instance, carries rollers 148 so as to minimize friction, the bearing of the cams being on said rollers.

The rollers are on the end portions of the pin 145 and the middle portion of said pin is screwed into a slide 149 that moves in guide grooves 150 formed in the inner faces of the cover plates 139. The slide 149 is provided at one end axially thereof with a longitudinally extending slot 151, through which extends a pin 152 whose ends are secured in cover plates 153. The pin 152 and slot 151 constitute a lost motion connection between the slide 149 and a universal joint 154, which serves to connect the lost motion connection with the rod 44 that passes axially through the head 110, being shiftably mounted in said head. The universal connection 154 comprises a fork 156 formed on the upper end of a link 157, a pin 158 connecting the fork 156 and slide 149, a fork 159 formed on the lower end of the link 157, and a pin 160 connecting the fork 159 with a socket member 161 into which the rod 44 is screwed.

The cam 143 includes a pair of rollers 162, 163 which bear against the lower ends of the valve stems 136, 137, and the cam 144 includes rollers 164, 165 that bear against the upper ends of the valve stems 141, 142. The cam slots 146, 147 are arranged at an angle with reference to the longitudinal axes of the cams so that rocking of the cams is produced when the slide 149 is moved longitudinally by actuation of the rod 44.

The cam 143 rocks on a pivot 166, the ends of which are seated in the cover plates 153, and the cam 144 rocks on the pin 152. The cover plates 153 are secured by screws 167 to the cover plates 139, and all of said cover plates constitute portions of the body 108.

The valves are retracted by coil springs 168, which always tend to hold the valve stems engaged with the several rollers which actuate them. The springs 168 surround

the valve stems, seating at one end against the heads 109, 110, as the case may be, and against spring seats, or abutments, 169 secured to the valve stems.

5 Surrounding the adjacent ends of the heads 109, 110 and closely fitting said heads, is a tubular housing or casing 25, the lower end of said casing seating against an annular shoulder 171 on the head 110, and the 10 upper end of said casing being engaged by the lower end of a nut 172 which is screwed onto the head 109. This nut 172 secures the casing 25 in place.

The upper end of the head 109 is screw-threaded at 175 so that the tubing 23, carrying the power fluid, can be screwed on to said head. The lower head is screw-threaded at 174 so that the cylinder 28 can be screwed thereon, the outside diameter of 20 the cylinder being less than the inside diameter of the tubing 27 so as to produce the annular passage 30 for the operating fluid, as will be made clear hereinafter.

As stated above, the tubing 27 connects 25 with one end of the cylinder of the pump and the cylinder 28 will connect with the other end of said cylinder.

A means is provided to releasably hold the rod 44 in two different positions against longitudinal movement. For this purpose the rod 44 is provided with an enlargement 176 containing in its periphery a series of notches 177 adapted to be engaged by detents 178 positioned at opposite sides of the rod. The 30 detents on each side will be one less than the number of notches on each side and, though the detents and notches may be provided only on one side, I have shown them on both sides. The detents 178 are yieldingly held in some of the notches by coil 35 springs 179 mounted in spring chambers 180 formed in the head 110. In this particular instance, the head 110 is constituted by two sections joined by a coupling 181 and the 40 two head sections are spaced to form a chamber 182 into which the valve 51 projects. The combined pressures of the springs 179 will be such that the force, tending to move the rod 44, will reach a predetermined value 45 before the rod 44 is released from the detents.

The provision of the chamber 138 affords opportunity to immerse the friction parts of the mechanism in a lubricant and if a 50 liquid is employed for the power fluid, it is desirable that said power fluid be maintained separate from the lubricant. If, for example, oil is to be used as the power fluid, said oil may be, or may become, charged 55 with foreign particles that it is desirable to exclude from the lubricant in the chamber 138. While this may be approximately attained without the use of any special device, it will be readily understood that because of movement of the rod 44 in and out

of the chamber 138, a breather duct must be provided which will communicate the chamber 138 with the interior of the tubing 23. The breather duct is indicated at 60 183 extending from end to end of the head 109. If the upper end of the breather duct 183 opened directly upwardly into the tubing 23, it will be readily seen that as the lubricant surges up and down in the duct 183, the power oil in contact with said lubricant might, in the course of time, become mixed therewith, and the heavier particles, at least, and, more especially, foreign particles, might gravitate downwardly and finally enter the chamber 138. To avoid 70 this, I preferably extend the duct 183 upwardly above the upper end of the head 109, thence downwardly so that the outer end of said duct opens downwardly as indicated at 75 184, thus making it practically impossible for foreign particles to enter the duct and, in fact, tending to prevent mixing of the lubricant with the power oil.

At the highest point in the duct 183 is a filling opening 185 normally closed by a 80 plug 186. After the valve mechanism is assembled, the lubricant will be supplied through the opening 185 up to the level where the duct turns downwardly and the plug 186 will then be screwed in the said opening. The filling will be effected when the rod 44 is at the lower end of its stroke and, thus, when the power fluid is in the tubing 23, it will ascend to meet the level of the lubricant. When the rod 44 moves upwardly, the lubricant in the duct 183 will be forced down the duct toward the open 90 end 184 and, hence, power oil will surge up and down in the short leg of the duct and not tend to mix with the lubricant.

The valve mechanism described above operates as follows: it will be assumed that the power fluid is supplied to the tubing 23 under pressure by the pump, that the valves 49, 51 are closed, and valves 48, 50 open, 100 as in Figure 12. The power fluid passes from the tubular member 23, through the port 52 into the passage 114, thence through the tubular section 112, passage 116, to the upper end of the cylinder 28 to actuate the piston on its down stroke. The power fluid beneath the piston will be forced upwardly 105 through the tubing 27, thence through the chamber 138 and port 54 to the exterior of the valve mechanism.

The connection between the rod 44 and the piston is such that there will be a certain amount of lost motion between the rod and the piston on both strokes of the piston. Assuming, then, that the piston has descended sufficiently far to pull the rod 44 downwardly, thus releasing it from the detents 178, said detents will again engage in certain of the notches 177 and hold the rod 110 in its lower position. Downward move- 120

ment of the rod 44 rocks the cams 143, 144, thus reversing the positions of the valves, opening the valves 49, 51 and closing the valves 48, 50. The power fluid now passes 5 from the tubing 23 through the port 53, thence through the passage 113, tubular section 111, and the passage 115, into the tubing 27, thence to the lower end of the cylinder so as to actuate the piston on its up 10 stroke. The power fluid previously forced into the upper end of the cylinder will now be forced by the piston upwardly past the valve 51, through the port 58, to the exterior of the valve mechanism. 15 The pump above described operates as follows: Assuming that the working parts of the pump are in the positions shown in the drawings, in other words, that the piston and plunger are at the upper end of 20 their strokes, and that the valves 48, 50 are open and the valves 49, 51 closed, the power fluid in the tubing 15 passes the valve 48 and through the port 52 into the tube 59, thence to the upper end of the cylinder 25 above the piston 45, forcing said piston downwardly and with it the pump plunger.

On the down stroke of the plunger, the standing valve 33 is closed and the plunger valves 37, 38 opened to admit fluid from beneath the plunger to the interior of said plunger and to the space within the cylinder above the plunger. On the down stroke, the rod section 41 passes into the upper end of the working barrel, displacing some of 30 the fluid from said working barrel through the ducts 80, chamber 79 and ports 81 into the tube 56, and fluid in the tube 56 is forced upwardly through the ducts 82, thus displacing the fluid in the casing above the packer 35 40 from said casing into the pipe line 84. The power fluid in the cylinder below the piston is forced by the descending piston out through the ports 29 into the tube 27, thence past the valve 50 through the port 54 into the tube 56. This exhaust power fluid then ascends with the fluid being pumped.

When the piston descends to a point that causes engagement of the piston with the shoulder 46, said piston actuates the rod 44 50 which operates the valve mechanism to close the valves 48, 50 and open the valves 49, 51. The power fluid then passes from the tubing 15 into the port 53, thence through the tubing 27 and ports 29 to the lower end of the cylinder below the piston, thus driving said piston upwardly. The power fluid above 55 the piston is now forced by the ascending piston through the tube 27, thence past the valve 51 through the port 58 into the upwardly ascending fluid being pumped within the tube 56. The ascending piston carries with it the pump plunger, the valves 37, 38 of which close and the plunger thus raises the fluid thereabove so that said fluid passes

upwardly the same as hereinbefore described for downward motion of the plunger.

When the plunger moves upwardly the standing valve 33 opens, thus admitting fluid from the well into the working barrel. When the piston rises sufficiently far 70 to engage the shoulder 47 on the rod 44, it actuates said rod which, in turn, operates the valve mechanism 26 so as to again open the valves 48, 50 and close the valves 49, 51. 75 The foregoing described cycle will then be repeated as long as the power fluid is supplied to the tubing 15.

In the operation of setting the packer, when the tubing 15 is turned to effect increasing of the packer member 62 from the packer member 64, the member 64 is held against turning by reason of the frictional grip of the lower end of the gas anchor 34 on the formation forming the bottom of the well and this frictional grip may be enhanced by providing the lower end of the gas anchor with a number of radial arms 86.

In the instance illustrated, the packing material 66 is enclosed by a sleeve 87 of readily rupturable material such, for example, as thin copper, so as to protect the packing material from friction with the casing when the packer is being lowered into the well. When the packer is released, as hereinbefore described, the thin metal sleeve 87, if it has not previously been ruptured by the outward pressure against it, will rub on the rough inner surface of the casing and in consequence will quickly disintegrate, thus allowing the packing material 66 to contact with the casing and be disintegrated in its turn.

I claim:

1. A fluid-operated pump comprising inner and outer tubings, the outer tubing provided with a perforated portion, a packer between the tubings and above the perforations, a working barrel in the outer tubing below the packer connected to discharge the pumped fluid into one of said tubings, a standing-valve for the working barrel, a valved plunger in the barrel, a fluid operated motor in the inner tubing operably connected with the plunger, and a valve mechanism connected with the tubing that does not receive the pumped fluid operable by the motor to control the flow of an operating-fluid under pressure from said last mentioned tubing to the motor.

2. A fluid-operated pump comprising inner and outer tubings, a means operable from a retracted condition into an expanded condition to separate one of the tubings into upper and lower passages, and a means operable by a power fluid within the inner tubing to pump a liquid from the lower passage through the upper passage.

3. A fluid-operated pump comprising

inner and outer tubings, a means operable from a retracted condition into an expanded condition by relative motion between the tubings to separate the outer tubing into upper and lower passages, and a means operable by a power fluid within the inner tubing to pump a liquid from the lower passage through the upper passage.

4. A fluid-operated pump comprising inner and outer tubings, a packer operable by downward movement of the inner tubing from a retracted position into an expanded position to separate the outer tubing into upper and lower passages, said packer releasable by upward movement of the inner tubing, and a means operable by a power fluid within the inner tubing to pump a liquid from the lower passage through the upper passage.

5. A fluid-operated pump comprising inner and outer tubings, a packer between the tubings separating the outer tubing into upper and lower passages, a tube sealed to the packer at its upper end, the packer provided with ducts therethrough communicating with the bore of said tube, a working barrel communicating at its upper end with the bore of the tube, a standing valve for the working barrel, a valved plunger in the working barrel, a fluid operated motor operably connected with the plunger, and a valve mechanism operable by the motor to control the flow of an operating fluid under pressure within the inner tubing to the motor.

6. A fluid-operated pump comprising inner and outer tubings, a packer between the tubings separating the outer tubing into upper and lower passages, a tube sealed to the packer at its upper end, the packer provided with ducts therethrough communicating with the bore of said tube, a working barrel communicating at its upper end with the bore of the tube, a standing valve for the working barrel, a valved plunger in the working barrel, a cylinder, a piston in the cylinder operably connected with the plunger, a tube surrounding the cylinder and communicating at its lower end with the lower portion of the cylinder, and a valve mechanism operable by movement of the piston to admit power fluid from the inner tubing to the upper ends of the cylinder and last mentioned tube and to exhaust the power fluid from the upper ends of the cylinder and last mentioned tube into the first mentioned tube.

7. A fluid-operated pump comprising inner and outer tubings, a packer between the tubings separating the outer tubing into upper and lower passages, the inner tubing formed of sections, one section telescoped within another, the inner section having a perforate portion spaced from the outer tubing, a standing valve for the working bar-

rel, a valved plunger in the working barrel, a fluid operated motor operably connected with the plunger, and a valve mechanism controlling the flow of power fluid from the perforate section to the motor.

8. A fluid-operated pump comprising inner and outer tubings, a packer between the tubings separating the outer tubing into upper and lower passages, a tube sealed to the packer at its upper end, the packer provided with ducts therethrough communicating with the bore of said tube, a seat member connected with the lower end of the tube, a coupling member loosely engaging the seat member and provided with a port communicating with the bore of the tube, a working barrel connected with the coupling member and communicating with the port, a standing valve for the working barrel, a valved plunger in the working barrel, a cylinder in the tube connected with the coupling members, a piston in the cylinder operably connected with the plunger, a tube surrounding the cylinder and communicating at its lower end with the lower portion of the cylinder, and a valve mechanism operable by movement of the piston to admit power fluid from the inner tubing to the upper ends of the cylinder and last mentioned tube and to exhaust the power fluid from the upper ends of the cylinder and last mentioned tube into the first mentioned tube.

9. A fluid-operated pump comprising inner and outer tubings, a packer between the tubings separating the outer tubing into upper and lower passages, a tube sealed to the packer at its upper end, the packer provided with ducts therethrough communicating with the bore of said tube, a seat member connected with the lower end of the tube, a coupling member loosely engaging the seat member and provided with a port communicating with the bore of the tube, a working barrel connected with the coupling member and communicating with the port, a standing valve for the working barrel, a valved plunger in the working barrel, a fluid operated motor operably connected with the plunger, and a valve mechanism operable by the motor to admit power fluid from the inner tubing to the motor and to exhaust power fluid from the motor into the tube.

10. A fluid-operated pump comprising inner and outer tubings, a means to separate one of the tubings into upper and lower passages, the inner tubing connecting with the upper passage through the separating means, fluid-operated means within the outer tubing to pump a liquid from the lower passage into the inner tubing, a tube connected with said pumping means to supply a power fluid to the pumping means to operate said pumping means and having a perforate up-
